HORACE WHITTLE, OF NEW YORK, N. Y., ASSIGNOR TO WESTERN ELECTRIC COMPANY, INCORPORATED, OF NEW YORK, N. Y., A CORPORATION OF NEW YORK.

TRANSMISSION SYSTEM.

Application filed July 18, 1921. Serial No. 485,447.

This invention relates to transmission circuits and more particularly it relates to coupling means for line sections of different characteristic impedances.

5 As is well known, the maximum transfer of energy between two interconnected impedances takes place when the impedance of one of the elements matches the impedance of the other. Whenever these impedances are unequal, transition or reflection losses take place which cause a considerable reduction in the effective transmission therebetween.

In accordance with this invention, coupling means for two unequal impedances are provided, by means of which transition losses are substantially eliminated over a wide range of frequency, even where the ratio of the two impedances varies with the 20 frequency. In the case where the two impedances constitute signal transmission lines of different characteristic impedances, a telephone cable and an open wire line, for example, the preferred form of coupling 25 means comprises a two-winding transformer having one terminal of one winding connected to one side of the cable, one terminal of the second winding connected to one side of the open wire line, and the remaining terminal of each winding being connected through a condenser to the other sides of the cable and open wire line. It will be hereinafter shown that such a coupling means may be so designed that for high 30 frequencies the transformer constitutes the main coupling network, that for low frequencies, the coupling means acts as if the line were directly connected without any shunting devices, while for intermediate 35 frequencies, the coupling is due to both the condenser and the transformer.

This invention will be better understood by reference to the following detailed description taken in connection with the accompanying drawing, in which Fig. 1 illustrates a coupling means for two transmission lines of different characteristic impedances; Fig. 2 illustrates a coupling means of this invention which is balanced with respect to both sides of the line, and Fig. 3 shows the extent to which reflection losses are eliminated by this invention.

Fig. 1 illustrates the preferred type of coupling means provided, in accordance 45 with this invention, for the two line sections

to be interconnected thereby and comprising a telephone cable 10 and an open wire line 11. As is well known in the telephone art, the characteristic impedance of an open wire line is approximately constant over a wide range of frequencies and for illustrative purposes, it may be assumed that open wire line 11 has a characteristic impedance of approximately 600 ohms for frequencies from 135 cycles to 30,000 cycles. The characteristic impedance of a cable, however, varies considerably with frequency and in the case of an unloaded #13 gauge cable for 30,000 cycles has a characteristic impedance of the order of 140 ohms, for speech frequencies such as 800 cycles, has an impedance of the order of 230 ohms, and for ringing current frequencies such as 135 cycles, has an impedance of the order of 600 ohms. Due to the wide variation in the characteristic impedance of the telephone cable 10 with frequency, it follows that transition or reflection losses would occur if the cable were directly connected to the open wire line which has a characteristic impedance substantially independent of frequency. Since the two line sections would present the greatest unbalance for frequencies of the order of 30,000 cycles, it follows that the greatest transition loss occurs for those frequencies employed in carrier telephony. Curve 12 in Fig. 3 shows to what extent transition losses would occur for frequencies from 135 cycles to 30,000 cycles, if the line sections 10 and 11 were directly connected. In this figure, the abscissæ represent the various frequencies transmitted between the two line sections while the ordinates represent the number of effective miles of standard cable at 800 cycles of transition loss incurred. The horizontal base line in Fig. 3 therefore represents such a connection of the two lines that no transition loss takes place for any frequency, which would be the case if the two line sections were connected together by an ideal transformer for each frequency desired to be transmitted. Since from the values assumed above, the open wire line and the cable are of the same characteristic impedance for 135 cycles, curve 12 reaches the zero transition loss line at a frequency value corresponding to 135 cycles. The transition loss with the lines directly connected, increases rapidly with the frequency until, as shown, by curve 12, the transition loss

loss for frequencies from 25,000 to 30,000 cycles is of the order of two and one half miles of standard gauge cable. This loss of two and one half miles for carrier frequencies is quite objectionable and it is therefore desirable to avoid this direct connection whenever possible.

In accordance with this invention, it has been found possible to substantially eliminate transition losses between a telephone cable and an open wire line by such a coupling means as shown in Fig. 1, wherein the two line sections are shown coupled by a transformer 13 and a condenser 14. Winding 15 of transformer 13 has one terminal connected to one side of the cable while the other terminal is connected to condenser 14. Winding 16 has one terminal connected to one side of line 11 and has its other terminal connected to condenser 14. The other terminal of condenser 14 is connected to both the cable and the open wire line. It has been found that when the impedances of the cable and the open wire line are as mentioned above, winding 15 should have an inductance of approximately .0114 henrys, winding 16 should have an inductance of .052 henrys, and condenser 14 should have a capacity of .6 of a microfarad in the case where windings 15 and 16 are series aiding. With the two line sections connected by a transformer and a condenser of such values, the reflection loss incurred is as represented by curve 17 of Fig. 3, which indicates substantially no reflection losses from 30,000 cycles until the order of 1,000 cycles, while for 135 cycles, it has a reflection loss of 1.2 miles of standard cable. This reflection loss for ringing current frequencies, however, is not serious and may be more readily overcome than the two and one half miles loss obtained for the carrier frequencies by a direct connection. For carrier frequencies say from 10,000 to 30,000 cycles, condenser 14 is of negligible impedance so that transformer 13 acts as if it were directly connected across the line. For these frequencies, the impedance seen by looking through transformer 13 in the direction of line 11, will be of the order of 140 ohms, while the impedance looking through transformer 13 in the direction of the cable will be of the order of 600 ohms. For essential speech frequencies, however, 800 cycles for example, the condenser 14 will offer appreciable impedance to the currents so that part of the speech frequency currents will flow serially through windings 15 and 16, the remaining part flowing through condenser 14. This increase in the impedance of condenser 14 will cause the impedance across the points 20 and 21, looking through the coupling means to the open wire line, to be of the order of 230 ohms. For very low frequencies, such as 135 cycles, condenser 14 has such a high impedance that

the coupling means acts as if there was no shunting element present and practically all of the current for such frequencies flows serially through the windings 15 and 16, which is the result desired; since, for such frequencies, the cable and the open wire line have approximately the same characteristic impedance. The loss of 1.2 miles in the ringing current shown by curve 17 in Fig. 3, may be easily explained since for ringing currents, transformer 13 acts as a simple retard coil of low impedance at that frequency and consequently will generally produce some loss in transmission. It will be apparent that due to the fact that the retard coil tends to neutralize the capacity reactance of the cable the loss at 135 cycles occasioned by the introduction of the retard will be less than if the retard were inserted in a simple resistance circuit. In a particular case it may be possible to so design the retard coil with respect to the capacity of the cable that one is completely neutralized by the other, in which case there would actually be a gain in transmission between the cable and open wire line over the case where the two are connected by an ideal transformer.

The two coils of transformer 13 should preferably be connected in series aiding relation. This is because of the fact that the mutual inductance between the two transformer windings is equivalent to a simple inductance in shunt to the line and in series with condenser 14. When these two transformer windings are in series aiding relation, the simple inductance element presents a negative reactance in this path and consequently will never combine with the negative reactance of the capacity to form a series resonant path of practically no impedance for a frequency dependent upon their values. Such a resonant shunt would be objectionable in most cases since its resonating effect would be liable to occur at some frequency within the band of frequencies over which uniform transmission is desired.

In many cases it will be found desirable to have the coupling means of this invention so arranged as to be balanced with respect to each side of the transmission line. In such cases, the coupling means may take the form shown in Fig. 2, in which two separate transformers 25 and 26 are provided on opposite sides of a condenser 27. The transformers 25 and 26 comprise toroidal core members 28 and 29, and windings 30, 31, and 32, 33 respectively. As described above, it is preferable that windings 30 and 31, and windings 32 and 33 should be so wound on the toroidal cores that they are in series aiding relation. One advantage gained by having elements 25 and 26 separate transformers, is that the so-called "cross fire effects" in Morse telegraphy are avoided. If wind-

ings 30 to 33 were on the same core, telegraph signals in one side of the transmission line would tend to produce disturbance in the other side of the transmission line over which it is desired to transmit other telegraph messages independently.

It is to be understood that this invention is not limited to the particular form of coupling means described above for interconnecting a telephone cable with an open wire line, since it will be apparent to those skilled in the art that the coupling means of this invention may be variously modified without departing in any wise from the spirit of this invention in adapting the coupling means to the interconnection of impedance devices of various types and different characteristic impedances.

What is claimed is:

- 20 1. In a wave transmission system for transmitting signaling currents in the speech frequency range and signaling currents in the ultra speech frequency range, two lines of different characteristic impedances, coupling means for said lines comprising a transformer for transmitting both speech and ultra speech frequencies, and means cooperating with said transformer for preventing substantial reflection losses for the whole 30 range of frequencies.
- 25 2. In a wave transmission system for transmitting signaling currents in the speech frequency range and signaling currents in the ultra speech frequency range, two lines of different characteristic impedances, coupling means for said lines comprising a transformer having such an impedance ratio as to match the impedances of said line for frequencies in said last range for transmit-

ting both speech and ultra speech frequencies, and means cooperating with said transformer for preventing substantial reflection losses for currents of the whole range of frequencies.

3. Coupling means for two lines of different characteristic impedances comprising a condenser in shunt to said lines of high impedance to speech frequencies and of low impedance to ultra-audio frequencies, a magnetic core, an inductance in series with each line section and having a common terminal connected to said condenser, said inductances being wound on said core in series aiding relation and having such values that speech currents pass serially through said windings to a substantial degree while ultra-audio frequencies are transmitted between said line sections substantially entirely by virtue of the inductive coupling between said windings.

4. In a transmission system comprising two line sections for transmitting a plurality of ranges of signaling current said sections having different frequency-impedance characteristics, coupling means for said line sections comprising a condenser in shunt to said line sections and an inductance in series with each line and having a common terminal connected to said condenser, said inductances being inductively coupled, said inductances and said condenser being proportioned to have an impedance ratio varying with frequency such as to substantially match the impedances of said sections for all of said ranges.

In witness whereof, I hereunto subscribe my name this 15th day of July A. D., 1921.

HORACE WHITTLE.
